United States Patent Office

Des. 212,326
Patented Oct. 1, 1968

212,326

TOILET SEAT ELEVATOR

William R. Brewer, Arleta, Calif., assignor to Hamilton C. de Jong (doing business as Safety Brothers), Pasadena, Calif.

Filed Dec. 15, 1967, Ser. No. 9,804

Term of patent 14 years

(Cl. D23—71)

FIG. 1 is a top plan view of a toilet seat elevator, showing my new design;

FIG. 2 is a left side elevational view of the same;

FIG. 3 is a bottom plan view thereof;

FIG. 4 is a front elevational view thereof; and

FIG. 5 is a rear elevational view thereof.

I claim:

The ornamental design for a toilet seat elevator, as shown.
